CLAIM

I claim the ornamental design for an overhead structure for an infant seat, as shown and described.

DESCRIPTION

FIG. 1 is a perspective view of an embodiment of an overhead structure for an infant seat showing my new design;

FIG. 2 is another perspective view thereof;

FIG. 3 is front side elevation view thereof;

FIG. 4 is a rear side elevation view thereof;

FIG. 5 is a left side elevation view thereof;

FIG. 6 is a right side elevation view thereof;

FIG. 7 is a top plan view thereof; and,

FIG. 8 is a perspective view of another embodiment of an overhead structure for an infant seat showing my new design. The broken lines immediately adjacent solid lines represent bounds of the claimed design and environment while all other broken lines are directed to environment and are for illustrative purposes only. The broken lines form no part of the claimed design.
